SWITCH AND COMPUTER CONTROL FOR
FLUID DISPENSING PUMPS

William H. D. Brouse, Toronto, Ontario, Canada,
assignor, by mesne assignments, to John Wood
Manufacturing Company Inc., Conshohocken,
Pa.

Application August 19, 1938, Serial No. 225,782

7 Claims. (Cl. 221—95)

This invention relates to fluid dispensing pumps of the type used in automotive service station equipment in the sale of gasoline in which the fluid is elevated from a storage tank and forced through a suitable metering device to a delivery hose, said metering device operating a computing mechanism for indicating the amount of liquid dispensed and the computed value thereof and the principal object of the invention is to 5 safeguard the purchaser of liquid dispensed against either wilful or accidental computing of charges in excess of the value of liquid actually delivered, and further to avoid the injury of the mechanism through the application of force to 10 the starting mechanism when locked.

The principal features of the invention consist 15 in the novel construction and arrangement of a mechanism introduced between the motor switch control device and the computing mechanism whereby the motor switch-operating mechanism is locked at the completion of one dispensing operation and the motor cannot be restarted until the computer indicator mechanism is returned to zero, and whereby the computer resetting mechanism is locked during the operation of the motor. 20 A further important feature consists in the arrangement of a spring-controlled sliding connection between the starting and locking devices.

In the accompanying drawings

30 Figure 1 is an elevational view of a motor-starting mechanism illustrating the application of this invention thereto.

Figure 2 is an elevational view of the mechanism illustrated in Figure 1, taken at right angles to the view illustrated in Figure 1.

35 Figure 3 is an enlarged elevational view of the control mechanism arranged between the switch-operating mechanism and the computer mechanism, the parts being shown in position ready 40 for the starting of a portion of the motor.

Figure 4 is a view similar to Figure 3 showing the position of the parts after the motor has been started and showing the means for locking the computing mechanism in the locked position.

45 Figure 5 is a view similar to Figure 3 showing the position of the parts locking the switch-operating mechanism after the motor has been stopped.

50 Figure 6 is a view similar to Figure 3 showing the position of the parts during the resetting of the computer.

Figure 7 is an elevational view of the mechanism illustrated in Figure 3 taken from the opposite side.

Figure 8 is a vertical sectional view taken on the line 8—8 of Figure 3.

Figure 9 is a sectional detail of the connection between the switch control device and the switch.

In fluid dispensing pumps various types of computing devices are used and the resetting mechanism is operated by a mechanism connected with a shaft which in the present mechanism is indicated by the numeral 1, the outward end of which extends into a hub member 2 and is keyed 10 thereto by a pin 3 engaging the diametrically opposed slots 3' in said hub.

The hub 2 is rotatably mounted on a stud 4 secured in a supporting plate 5 within the casing of the pump and on the plate the hose hook 6, 15 for supporting the dispensing nozzle, is rigidly mounted.

A pair of plungers 7 and 8 are suitably mounted 20 in the plate 5 to engage the opposite ends of a rocker arm 9 pivotally mounted on an inward extension 10 of the hose hook and said rocker arm is formed with a centrally arranged lever 11 to which is pivotally secured a rod 12 which extends upwardly therefrom and is arranged at one side of the hub 2.

A rocker plate member 13 rotatably mounted on the stud 4 carrying the hub 2, is formed with a lug extension 14 upon which a stud 15 is pivotally mounted to extend at right angles therefrom.

The rod 12 extends through a hole in the stud 30 15 and a spiral compression spring 12' encircles the upper end of the said rod between the stud 15 and a washer 16 secured to the upper end of the rod so that if the member 13 is locked against rotation, the rod 12 may slide in the stud 15 35 against the compression of the spring, but if the member 13 is not locked the pull of the rod will swing said member on its pivot. A collar and cotter 15' returns the member 13 on pressing plunger 7.

40 A rod 17 extends through a hole in the stud 15 and is locked thereto by nuts 17' arranged on either side of the stud. This rod is connected to and operates the motor switch, represented at S Figure 2.

45 A disc 18 rigidly secured on the hub 2 is spaced from the plate 5 and is provided with a squared notch 19 in its periphery.

A latch arm 20 is pivotally mounted on a stud 21 secured in the plate 5 and said arm extends 50 over the periphery of the disc 18 and has a downwardly extending tooth 22 which is adapted to enter the notch 19 in the said disc to lock it and the hub 2 from rotation.

55 The free end of the arm 20 is connected by a

short link 23 to the rocker plate 13 so that when the plate is turned counterclockwise, through the operation of the rod 12, the arm 20 will be swung downwardly to the position illustrated in Figure 4.

5 A cam member 24 is fixed to the plate 5 and has a peripheral portion 25 arranged concentric with the disc 18 and of slightly lesser radius than the disc. This cam is formed with a V notch 26 in its periphery below the stud 4 and slightly to 10 one side of a vertical line extending from the axis of the stud.

A cam disc 27 is rotatably mounted on the hub 2 between the disc 18 and the fixed cam 24 and is provided with a concentric peripheral portion 15 of substantially the same or slightly greater radius than that of the fixed cam 24, said concentric portion having a lug 27' at one end.

A concentric slot 28 is formed in the cam disc 27 and a pin 29 secured in the disc 18 extends 20 thereto so that when the disc 18 is rotated, it will rotate the disc 27 with it, but the disc 27 may move a limited distance freely while the disc 18 is stationary.

The cam disc 27 is formed with a V notch 30 25 (see Figure 5) on the side facing the fixed cam 24, and a flat spring 31 is secured to the plate 5 and is provided with a flanged tip to engage said notch to hold the cam from reversing, but will not prevent said cam disc 27 from turning 30 with the disc 18 when the pin 29 engages the end of the slot 28.

A pawl 32 is pivotally mounted on the rocker plate 13 below the disc 18 and it is provided with an inverted V-shaped tooth 33, which engages 35 the peripheral surfaces of the cams 24 and 27. This tooth 33 is adapted to enter the notch 26 in the cam 24 and lock the member 13 from rotation. The pawl is actuated by a spring 34 arranged between the pawl and a lug 35 on the 40 plate 13.

In the operation of this device, when the computing mechanism has been reset after a dispensing operation, the hub 2 and the disc 18 are in the position illustrated in Figure 3, the notch 45 19 in the disc being arranged immediately below the tooth 22 of the arm 20.

The cam disc 27 has its larger radius lug portion 27' engaging the tooth 33 of the pawl, so it is held from entering the notch 26 in the fixed 50 cam 24. The starting plunger 8 may then be pressed inwardly to tilt the rocker arm 9 and pull downwardly on the rod 12 which, through the spring 12', swings the plate 13 on its pivot and operates the motor switch through the rod 17. 55 Simultaneously the arm 20 is swung downwardly through the link 23, and the tooth 22 enters the notch 19 in the disc 18 (see Figure 4). In this movement of the rocker member, the pawl engaging the lug 27' on the cam 27 turns the cam 60 27 to clear the larger radius portion from register with the notch 26 and the spring 31 engages and over-rides the notch 30 in the face of the disc 27. The disc and the computing mechanism are thus locked against resetting while the motor is running.

65 The motor is stopped by pressing in the plunger 7 which swings the rocker arm 9 and lifts the rod 12, thereby returning the member 13 clockwise to the position shown in Figure 5. The tooth 22 of the arm 20 will thereby be removed from notch 19 to clear the disc 18, and the pawl 32 displaced in a peripheral path to clear the larger radius portion of the cam disc 27 which is temporarily held by the spring arm 31. The tooth of the 70 pawl enters the V notch 26 in the fixed cam 24 75

immediately prior to the clearing of the tooth 22 from the notch 19 so that the motor switch is locked before the computer is released for resetting. The pawl thus locks the member 13 from being operated by the operation of the 5 plunger 8.

In the resetting of the computer mechanism, the shaft 1 thereof rotates the hub 2 and the disc 18 mounted thereon and, the pin 29, engaging one end of the slot 28, rotates the cam disc 10 27 until the raised portion thereof pushes the pawl 32 out of the notch 26, thereby unlocking the member 13 so that it may be operated, thus allowing the starting of the motor.

If the computer mechanism requires more than 15 one complete revolution and a partial return movement for resetting, the locking pawl 32 is released from the notch 26 prior to the return movement of the disc 18, so that the member 13 is locked until the notch 19 is brought back into 20 register with the tooth 22, which ensures the completion of the resetting cycle before the switch is released.

The mechanism is extremely simple and inexpensive, but it forms a very positive lock against 25 manipulating the computing mechanism while the motor is moving, or starting the motor without resetting the computing mechanism.

An important feature of the structure resides in the provision of the sliding connection between 30 the switch-operating device and the locking mechanism so that when the mechanism is locked the starting plunger may be operated without strain to the mechanism connected therewith. This provision enables the use of a light and inexpensive construction which may be manufactured at comparatively low cost.

What I claim as my invention is:

1. In a device of the class described having means to be controlled and resetting means for a 40 register or the like, a rocker member operatively connected with said means to be controlled, an operating rod having sliding engagement with said rocker member, a coil compression spring encircling said rod arranged between a stop on 45 said rod and said rocker member to operate said rocker member when it is unlocked and to permit said rod to slide when said rocker member is locked, a latch mounted on said rocker member, means for engaging said latch to lock said rocker 50 member, and means adapted to be connected with said resetting means for releasing said latch on the resetting of the register.

2. In a device of the class described having means to be controlled and resetting means for a 55 register or the like, a rocker member operatively connected with said means to be controlled, means for operating said rocker member, a latch mounted on said rocker member, fixed means adapted to engage said latch to lock said rocker 60 member, a rotary member adapted to be operatively connected with the resetting means, and a rotary cam operatively connected with said rotary member adapted to engage and release said latch.

3. In a device of the class described having 65 means to be controlled and resetting means for a register or the like, a rocker member operatively connected with said means to be controlled, means operatively connected with said rocker member to operate the same, a latch mounted on 70 said rocker member, fixed means adapted to engage said latch to lock said rocker member, a rotary member for operative connection with said resetting means, a pin extending from said rotary member, and a cam disc rotatably mounted 75

- co-axially with said rotary member having a concentric slot slidably receiving said pin and having a cam projection adapted on rotation to engage and release said latch on the rotation of said 5 rotary member by the resetting means.
4. A device as claimed in claim 3 having a lug on said cam disc to engage said latch to rotate said cam disc on the operation of said rocking member in one direction and move said cam projection clear of the fixed means for engaging and locking said latch and rocker member.
- 10 5. A device as claimed in claim 3 in which said cam disc is provided with a notch, and a fixed spring arm engages said disc and enters the notch therein to hold said cam disc from return movement after being moved by said latch to clear the latch locking means.
- 15 6. In a device of the class described having a motor switch control device and resetting means 20 for a register or the like, a rocker member operatively connected with said motor switch control device, means for operating said rocker member, a notched rotary member for operative connection with said resetting means, an arm mounted 25 on a fixed pivot having a tooth extension to enter the notch in said rotary member, a link connecting the free end of said pivotal arm with said rocker member, and means for locking said rocker member on the release of said pivotal arm from locking engagement with said notched rotary member.
7. In a device of the class described having 5 means to be controlled and resetting means for a register or the like including a shaft, a stud mounted in axial alignment with said shaft, a hub rotatably mounted on said stud and engaged to rotate with said shaft, said hub having a disc 10 provided with a peripheral notch, a pin extending from said disc, a cam disc rotatable on said stud and having a concentric slot receiving said pin and a concentric cam extension, a fixed member having a concentric periphery of substantially the same radius as the radius of said cam extension the periphery thereof having a notch 15 therein, a rocker member pivoted on said stud, a latch pivoted on said rocker member and having a tooth portion riding on the peripheries of said fixed notched member and said cam disc and adapted to enter said notch, a rod connecting said rocker member with said means to be controlled, and means connected with said rocker member for engaging the notch in the disc carried by said 20 hub, and means for actuating said rocker member.
- 25 WILLIAM H. D. BROUSE.
